ENTERTAINMENT DEVICE TO ACCOMPANY
PACKAGES OF MERCHANDISE

Jacob Warren Bowman, Philadelphia, Pa., assignor to Gum Inc., Philadelphia, Pa., a corporation of Pennsylvania

Application February 17, 1934, Serial No. 711,779

1 Claim. (Cl. 46—35)

My invention relates to entertainment devices which are enclosed in packages of merchandise.

A purpose of my invention is to enclose picture reproducing supplies and apparatus in packages of merchandise.

A further purpose is to enclose strips of translucent material with different part configurations thereon which are adapted to cooperate one with another along matching lines to produce unique designs.

A further purpose is to provide within merchandising packages, in the present instance, packages of chewing gum, sheets of sensitized paper, sheets of translucent material with part configurations thereon adapted to match with one another when placed along matching lines and means for holding the sensitized paper in contact with the translucent material to reproduce the combined configurations on a single sheet of paper to obtain an understandable subject matter when exposed to bright light and afterwards washed in water or other liquid for fixing.

Other purposes will appear in the specification and in the claim.

In the drawing I have illustrated one of the many possible embodiments of my invention, selecting a form which is convenient in use, easy to manufacture and satisfactory in demonstrating the principles involved.

Figure 1 is a perspective view of a merchandising packet, preferably a packet containing chewing gum and parts of the material for making up my invention.

Figure 2 is a transverse sectional view taken on the line 2—2 of Figure 1, somewhat enlarged to show thicknesses of material.

Figure 3 is a view similar to Figure 2, but showing another of the parts used to complete my invention.

Figure 4 is a view similar to Figures 2 and 3, but showing still another of the parts used to complete my invention.

Figure 5 is a perspective view showing the matching of translucent strips for reproduction purposes.

Figure 6 is a perspective view similar to Figure 5 but showing different configurations upon translucent material used in my invention.

Figure 7 is a perspective view of a device for holding the sensitized paper in contact with the translucent material for completing the subject matter according to my invention.

In the drawing similar numerals indicate like parts.

In manufacturing and selling chewing gum it has been found to be desirable to provide novel and entertaining devices to interest children.

I have also found that it is desirable to furnish within a packet, novelty subject matter which will depend for a full understanding or for completion, upon subject matter in another packet which is obtained by another purchase from that of the first mentioned packet.

In carrying out my invention I have found it desirable to place approximately 100 pieces of wrapped chewing gum in a box for delivery to a store keeper. From the box the store keeper retails the individual packets to the customers (who in the present instance are usually children between the ages of five and eleven).

In carrying out the detailed distribution of my improved entertainment device, I place one or more (preferably about three) pieces of sensitized paper such as blue print or printing out paper, or any other paper that may be used for contact printing by light exposure, within each package containing chewing gum. It is preferable of course to provide paper which will be placed in water for finishing and does not require any fixing solution to be used by the children.

Other boxes are filled with packets that have, within the chewing gum packets, pieces of translucent material with printed objects thereon. The printing on the translucent material is made into any desired configuration and within a given box all packets preferably contain different printing. The configuration on one strip of translucent material is arranged so that any one of the strips that are lined to match with the bottom strip will be in exact position to complete a figure, although the figure completed may have no counterpart in the world. For example, the figures produced may be anomalies of natural history, which will therefore seem more amusing to children who are beginning to become aware of the facts of the creature world. The lower portion of the figure may illustrate the body of a giraffe and the upper portion of the figure may represent a horse, dog or any other animal. It will be noted that many amusing pictures can be obtained by these combinations.

In another box of chewing gum I place in the individual packets of gum a holder into which the translucent strips may be placed above one of the sheets of sensitized paper, and the purpose of this holder for the sensitized paper and the translucent material with its printing thereon is to instruct the child to expose to a bright light

the translucent material, which constitutes in the present instance a film of the photographic type, and to allow the child actually to transfer the pictures from the translucent material to the sensitized paper. After the transfer, the child may wash the sensitized paper with water and display the pictures thereon that have been transferred from the translucent material.

In Figure 1 I have illustrated a packet according to my invention. In Figure 2 I have shown a transverse section through the packet of Figure 1 in which the chewing gum 11 has a wrapper 12 having overlapping edges 13 and turned end 14. In the wrapper 12 and with the gum 11 I place a number of strips of sensitized paper 15. The sensitized paper 15 should be only moderately sensitive to light. This is true of blue print paper and printing out paper.

In Figure 3 I have shown a section of a packet similar to Figure 2, but in this illustration I have shown in the packet above the chewing gum 11 a strip of translucent material 16 having printed objects thereon. The material 16 may, for example, be tracing paper, tissue paper, tracing cloth or cellophane. In all other respects this packet is the same as that of Figure 1.

In Figure 4 I have illustrated a packet similar to that shown in Figures 2 and 3. In this packet I show a holder 17 which is adapted to support the sensitized paper on its bottom and to hold the translucent material superimposed upon the sensitized paper. The edges 18 and 19 of the holder 17 are adapted to hold the edges of the sensitized paper and translucent material in place in the holder 17 in order to allow the user to expose the holder and its contents in a bright light for a sufficient length of time to allow for the transfer of the combined picture of two translucent strips which are placed in the holder above the sensitized paper.

In Figure 5 I have shown a perspective view of two strips 16 and 16' of translucent material. The strip 16 is supplied with controlling or longitudinal matching lines 20. Transverse matching lines 21 are indicated on the surface of the strip 16.

The matching lines 20 are arranged in such a manner that, if the child will follow them carefully in attempting to match an upper section 50 with a lower section, he will be able to have the two parts of his translucent material match perfectly. I have found overlapping of the sections 16 and 16' to be desirable because it allows for the proper lining up of the two strips of translucent material much more satisfactorily than would be the case if an attempt were made to place the ends of the two strips together for matching purposes, because the overlapping ends 55 provide a proper matching space between the upper and lower sections of translucent material.

In the showing of Figure 6 I have used the same lower translucent strip 16 but, in place of the strip 16' of Figure 5, I have illustrated a strip

16² which contains a different upper configuration from that of the strip 16'.

In Figure 7 I have illustrated the holder 17 carrying a strip of sensitized paper 15 with the strips of translucent material 16 and 16' properly aligned and in place thereon. The translucent and sensitized materials are held in place in the holder 17 on account of the upward curve at 22 of the body of the holder 17, which curved portion 22 impinges against the translucent and sensitized papers and tends to bow them outwardly and hold them firmly in place. At the same time the gripping edges 18 and 19 of the holder 17 support the edges of the strips 15 and 16.

It is not necessary that the holders 17 be placed 15 with a piece of chewing gum within the wrapper of the packet 10, as I have found it is sometimes preferable to allow the store keeper to distribute the holders among different children at his discretion. A careful child may even use the translucent material and the sensitized paper without a holder.

My arrangement of pictures will present many other possibilities than those mentioned as they may contain the body of an animal on one section 25 and the head of a person on the other section and by use of the matching lines 21 many amusing combinations can be secured. The child will of course seek to place the head and body of the same animal on the same picture. This is ac- 30 complished in some cases by trading pieces of translucent material among the children.

The use of blue print paper and printing out paper is so well known that I will not attempt to explain it in detail. My invention relates both 35 to the methods involved and to the articles used.

In view of my invention and disclosure, variations and modifications to meet individual whim or particular need will doubtless become evident to others skilled in the art to obtain all or part 40 of the benefits of my invention without copying the structure shown, and I therefore claim all such in so far as they fall within the reasonable spirit and scope of my invention.

Having thus described my invention, what I 45 claim as new and desire to secure by Letters Patent is:-

In an amusement device for distribution with an article of manufacture, the combination of a sheet of light sensitive paper, a plurality of translucent sheets having configurations thereon, superimposed upon the light sensitive sheet and cooperating to form a complete configuration to be reproduced upon the light sensitive sheet, and a holder presenting an outwardly bowing surface 50 to the light sensitive paper and presenting in front of and along the sides of the outwardly bowing surface inwardly directed runway surfaces to the outer surfaces of the translucent sheets along the edges thereof, whereby the sheets are 55 bowed against their resilient flattening force and held frictionally together by their own tendency to flatten.

JACOB WARREN BOWMAN.
